Filed July 30, 1968, Ser. No. 12,958

Term of patent 14 years

Int. Cl. D21—01

U.S. Cl. D34—13

FIG. 1.

FIG. 2.

FIG. 3.

FIG. 4.

FIG. 5.

FIGURE 1 is a top plan view of a poker chip dispensing device, showing my new design;

FIGURE 2 is a front elevational view thereof;

FIGURE 3 is a side elevational view thereof as seen by looking at FIG. 1 from the right;

FIGURE 4 is a rear elevational view thereof; and

FIGURE 5 is a bottom plan view thereof.

The broken line showing of a column of poker chips in FIGS. 1 and 2 is for illustrative purposes only.

It is to be understood that the handle of the device, which is shown in central location in FIG. 1, is movable to a raised, or elevated, position.

I claim:

The ornamental design for a poker chip dispensing device, substantially as shown and described.
